UNITED STATES PATENT OFFICE.

SAMUEL HOUSTON, OF ST. LOUIS, MISSOURI, ASSIGNOR OF ONE-FOURTH
HIS RIGHT TO LEWIS A. CLARKE, OF SAME PLACE.

IMPROVEMENT IN WOOD PAVEMENTS.

Specification forming part of Letters Patent No. **171,619**, dated December 28, 1875; application filed
October 23, 1875.

To all whom it may concern:

Be it known that I, SAMUEL HOUSTON, of the city and county of St. Louis and State of Missouri, have invented a new and useful Improvement in Pavement, which improvement is fully set forth in the following specification, reference being had to the accompanying drawings.

My improvement consists in a pavement which is formed of blocks of any description of timber, beveled at their sides at the upper portion. The blocks are grooved horizontally at the sides, to admit the edges of the longitudinal and lateral frame-work bars, by which the blocks are held in their relative vertical position.

In the drawings, Figure 1 is a perspective view of a small section of pavement. Fig. 2 is a side view of a block. Fig. 3 is an end view of a block.

The blocks may be of any suitable dimensions, and are preferably laid with the grain running vertically, as is usual with wooden pavements.

On the ends of the blocks A are rectangular grooves B, extending horizontally from side to side, and at the sides are similar grooves C, extending from end to end. The grooves B receive the edges of the frame-bars D, which extend longitudinally with the street, and the grooves C receive the edges of similar bars E, which extend transversely to the street. The bottoms of the bars D are shown in contact with the tops of the bars E, but it is not material which set of bars has the top and which the bottom position. The blocks A may be placed on a foundation of boards laid flat, or they may set on a foundation of gravel, sand, or any other suitable material. From the grooves B and C the sides are beveled upward, as shown at a, so as to form angular spaces

between the upper portions of the blocks, for the reception of asphalt, gravel, and pitch, or any similar material, which would tend to fix the blocks more firmly in position or render the pavement less pervious to moisture.

In constructing the pavement, the blocks may be placed in a row across the street, and the ends of the frame-bars D being held between the blocks, said bars extend horizontally and at right angles from the row of blocks. Then one line of transverse bars E is placed in position, and the edges driven into the grooves C. Another transverse row of blocks may then be put in position, and another line of bars E, and so on, the blocks fitting tightly together at their bottoms, and the bars D E being completely enveloped in the grooves B C. The asphalt or other material is then forced into the angular spaces F.

It will be seen that even before the addition of the asphalt the locking-bars D E will effectually prevent the tilting or vertical shifting of the blocks A, as no block can shift in any way without causing an equal movement to a number of others, and also the distortion of the timber.

I claim as my invention—

The blocks A, fitting firmly together for some distance upward from the bottom, and beveled from that point upward, to form, when placed together, a recess transverse to the street, for the reception of cement, and to afford a hold for the feet of horses, in combination with the frame, consisting of longitudinal and transverse bars let into the sides of the blocks so deeply as to allow the blocks to stand closely together, substantially as set forth.

SAMUEL HOUSTON.
